LIGHT TRACK SUPPORTING CLIP

William M. Armstrong, El Cerrito, Calif., assignor to
Lektra Lighting, Inc., San Francisco, Calif.

Filed Mar. 18, 1974, Ser. No. 452,787

Term of patent 14 years

Int. Cl. D8—08

U.S. Cl. D8—259

FIG. 2

FIG. 3

FIG. 1

FIG. 4

FIG. 5

FIG. 6

FIG. 7

FIG. 1 is a top plan view of a light track supporting clip showing my new design;

FIG. 2 is a front elevational view;

FIG. 3 is a side view;

FIG. 4 is another side view;

FIG. 5 is a rear elevational view;

FIG. 6 is a bottom plan view; and

FIG. 7 is a perspective view.

I claim:

The ornamental design for a light track supporting clip, substantially as shown.
